UNITED STATES PATENT OFFICE

2,136,634

AIR CONDITIONER

James E. Peoples, Alva, Okla.

Application June 21, 1937, Serial No. 149,397

1 Claim. (Cl. 261—92)

My invention relates to an air conditioner in which air is circulated through moisture, discharging the same through a suitable conductor for cooling and humidifying the atmosphere of any enclosed place of habitation.

The object of my invention is to provide an efficient air conditioner, inexpensive in its construction and installation.

A further object of my invention is to provide an air conditioner, portably or stationarily arranged and inexpensive to operate.

A still further object of my invention is to provide an air conditioner, operative by air circulating through the mechanism, the current for which may be by motor driven fan or by natural currents of any kind.

A still further object of my invention is to provide a simple and efficient means to control the circulation of air, with respect to volume desired and means to vary the humid condition.

These and other objects will hereinafter be more fully explained, reference being had to the accompanying drawings forming a part of this specification, and in which like characters will apply to like parts in the different views.

Referring to the drawings:—

Fig. 1 is a side view of the mechanism, parts removed for convenience of illustration.

Fig. 2 is a front end view, parts removed for convenience of illustration.

Fig. 3 is a plan view partly in section.

Fig. 4 is a perspective view of one of the screen elements showing a preferred method of hanging the screen to its rod support.

Fig. 5 is an enlarged view of the rotor shaft bearing.

Fig. 6 is an enlarged sectional view through one side of the damper control and lid, taken on lines 6—6 in Fig. 1.

The component parts of my invention herein disclosed, consists of a housing 1 in which is trunnioned a rotor later described.

Extending from one end of said housing is a duct 2 as an exit discharge for the housing, and in which is positioned a motor driven fan 3, as mechanical draft creating means for air to enter the housing and be discharged outward through said duct.

In the end of the housing opposite the duct 50 is an air inlet opening as at A, through which air will enter as shown by the form, the direction of draft being shown by the arrows.

The upper side wall of said opening is formed by a damper 4, hinged as at B, to a lid 5 and 55 adapted to rock to and from the opening as

shown by dotted lines to vary the size of the opening, the lid as closing means for the top of said housing is hingedly connected as at C, by which means, when the lid is swung, as shown by a dotted line, to a wide open position, the rotor 5 can be removed and replaced as said rotor shaft is trunnioned in U-shaped bearings 6, that is secured to the inside of each side wall of the housing.

Secured to each of the side edges of the lid 10 and damper is a pair of flanges 7, to slidably engage over the side edges at the upper end of the housing, by which means the joints thus treated are practically air tight and the said damper and lid retained in proper registry with 15 the walls of the housing.

Trunnioned in the said housing is a rotor comprising a shaft 8, the ends of which are seated in their respective bearings 6.

Axially secured to the shaft and spaced a short 20 distance from each end thereof is a disc 9, said discs being joined by a plurality of rods 10, spaced there-around in close proximity to the periphery of the discs forming the rotor, each rod having a flap 11, of woven wire fabric placed thereon, the said flaps extending from one disc to the other, and of such width as to avoid contacts with the adjacent rods during rotation of the rotor, it being understood, that the flaps are pendently carried by their respective rods and 30 adapted to turn thereon, maintaining a vertical position, while the rotor turns on its axis, the purpose of which is to submerge the flaps in water or other liquid as shown at D in Fig. 1, and each of said flaps as they immerge from the 35 fluid will carry the same by capillarity as the flaps are moved upward and over, when the rotor turns, the motor power being through the medium of air current created by the said motor driven fan, directionally as indicated by a plurality of arrows shown in Figs. 1 and 2.

The air current entering at opening A, will impinge the flaps, turning the rotor causing evaporation of the fluid carried thereby, cooling the 45 air as discharged outward through duct 2, reconditioning the atmosphere of dwelling rooms, auditoriums or the like.

I have also arranged a fluid supply pipe 12, and an automatic cutoff actuated by a float 13, as 50 means to govern the proper depth and amount of fluid required for efficient performance of the device.

This invention may also be applied for other purposes, that is to say a disinfectant or other 55

medicinals may be placed in the water and discharged with equal efficiency.

The disclosed structural form may be varied and such other modifications may be made as lie within the scope of the appending claim.

Having fully described my invention, what I claim as new and desire to secure by Letters Patent is:—

In an air conditioner, a housing adapted to 10 contain liquid therein, a lid engaging the upper extremity of the housing, a damper hingedly carried by the lid and adapted to move to and from an opening in the housing as controlling means for a current of air drawn through the 15 housing, a fan to create a current by suction through the housing and outward therefrom, a rotor trunnioned in the housing, the rotor comprising a shaft, a disc secured a spaced distance

from each end of the shaft, each being in close proximity to its respective side wall of the housing, a plurality of rods connecting the discs, and being spaced therearound in close proximity to the periphery of the discs, a woven wire flap 5 for each rod pendently carried thereby, the flaps being rectangular in form and of length to extend from disc to disc and free to turn on the rods maintaining a vertical position while the rotor turns said rotor being so positioned in said 10 housing that the upper flaps are situated in and transverse to said air current drawn through said damper, while the lower flaps are submerged in the liquid, whereby the rotor is turned by said air current and the flaps successively moistened and presented to said air current. 15

JAMES E. PEOPLES.
